COMBINED PRESSURE-SENSITIVE ADHESIVE TAPE DISPENSER AND APPLIER

John A. Polster, St. Paul, Minn., assignor to Minnesota
Mining and Manufacturing Company, St. Paul, Minn., a corporation of Delaware

Application July 12, 1956, Serial No. 42,226

Term of patent 14 years

(Cl. D74—1)

FIG. 1

FIG. 2

FIG. 3

FIG. 4

Figure 1 is a perspective view of a combined pressure-sensitive adhesive tape dispenser and applicer showing my design;

Figures 5 and 6 are front and rear elevational views, respectively.

I claim:

The ornamental design for a combined pressure-sensitive adhesive tape dispenser and applicer, as shown.
